UNITED STATES PATENT OFFICE

2,287,702

FUEL INJECTION DEVICE

William M. Nichols, Auburn, N. Y., assignor to
 American Locomotive Company, New York,
 N. Y., a corporation of New York

Application May 15, 1941, Serial No. 393,643

1 Claim. (Cl. 123—139)

This invention relates to fuel injection devices for internal combustion engines.

The present invention is an improvement of the type of fuel injection device in which a fuel pump delivers fuel under pressure to an injector nozzle, the valve of which is actuated by the fuel under pressure.

Such fuel injection devices have been found to have certain undesirable characteristics, especially when used in high speed Diesel engines. For instance, it has been found that when such a fuel pump is employed to supply fuel under pressure throughout the entire range of speeds of a high speed engine, the rate of injection throughout the reduced speeds of the range is undesirably correspondingly reduced, due to the reduced velocity of the pump. Also when the engine is running at the higher speeds of the range, extreme pressure waves are created in the pipe between the fuel pump and injector nozzle, due to the sudden spill of the fuel to terminate injection. These pressure waves have a tendency to open the nozzle valve, thereby causing a second and perhaps a third injection at a time undesirable for proper operation of the engine. Furthermore, as the conventional pump, in a single pumping operation, is required to build up the pressure to a point where the nozzle valve will open, then to maintain the pressure during injection, and thereafter to spill the fuel to terminate injection, the period of injection is consequently undesirably long. The elimination of one or more of these steps permits a shorter injection period to be obtained.

It is an object of the present invention to provide a fuel injection device which will not have the aforementioned undesirable characteristics.

A further object is to provide an improved injector nozzle.

A further object is to provide a fuel injection device in which two separate fluid pumps coact to effect injection, one pump providing fuel to the injector nozzle, and the other providing a fluid for actuating the nozzle valve.

Other and further objects of this invention will appear from the following description, the accompanying drawing and the appended claim.

Referred to the drawing forming a part of the present application, Figure 1 is a diagrammatic view in vertical central section illustrating one embodiment of the fuel injection device of the present invention, parts being shown in full and other parts broken away; Fig. 2 is a diagrammatic view, in elevation, of a modification of the

invention, parts being broken away; and Fig. 3 is a diagrammatic plan view of an internal combustion engine, showing the arrangement of the fuel injection devices therefor of the type illustrated in Fig. 1.

Referring to Fig. 1, the fuel injection device, indicated generally by the reference numeral 1, includes an injector nozzle 2, a fuel pump 3 connected to the nozzle by a pipe 4, and a smaller valve-actuating fluid pump 5 connected to the nozzle by a pipe 6.

The fuel pump 3 is illustrated as of the plunger type, although other types of pumps may be employed if desired. Similar remarks apply to pump 5, but the following description will be limited to the type of pump shown, as it has been found that this type is especially well adapted to the present invention.

Pump 3 includes a body 1 having a cylinder 8, a cap 9 therefor, fuel inlet pipe 10, fuel discharge passage 11, plunger 12 and check valve 13. Pump 5 similarly includes a body 14 having a cylinder 15, cap 16 therefor, fluid inlet pipe 17, fluid discharge passage 18, plunger 19 and check valve 20.

Pump 3 controls the period during which fuel is delivered to the nozzle 2. Pump 5 controls the period during which the nozzle valve (later to be described) is maintained in open position. Injection may commence when the nozzle valve is opened, provided fuel under pressure has already been delivered to the nozzle, or it may commence when fuel is delivered to the nozzle, provided the nozzle valve is already open. Similarly injection may be terminated by the closing of the nozzle valve or by pump 3 terminating delivery of fuel to the nozzle.

It has been found preferable to operate the pumps so that pump 3 begins to pump before and continues to pump after pump 5, so that a constant supply of fuel under pressure is available during the period in which the nozzle valve is kept open by pump 5. Thus pump 5 determines the beginning and the end of injection. This insures a quick commencement of injection and a quick termination, avoiding dribbling of fuel into the engine cylinder at the beginning and end of injection, which dribbling effects poor combustion in the cylinder. This is an added advantage of the present invention.

Where, as in the present case, the commencement and termination of injection are controlled by the pump 5, pump 5 must be adjustable to permit the engine to run at different speeds. Adjustable pumps are well known and for this

reason pump 5 has been shown more or less diagrammatically in Fig. 1, no detailed description of an adjustable pump being deemed necessary. An adjustable pump which may be employed to do the work of pump 5 is shown in patent to Baur, 1,871,872, dated August 16, 1932.

Fuel pump 3 may be adjustable or not, depending upon the manner in which it is employed. When an adjustable fuel pump is to be employed, it may be similar to the pump of the above mentioned patent. While, as stated, the pumps are shown diagrammatically, it will be noted, however, that the metering groove of the patent which is responsible for the adjustability, is indicated on each of the plungers 19 and 12 of the pumps 5 and 3. Obviously, when pump 5 controls the commencement and termination of injection, pump 3 need merely supply enough fuel to nozzle 2 so that fuel under pressure will be available during the time the nozzle valve is in open position. If a by-pass is provided to prevent undesirable pressures at certain speeds, a pump 3 can be utilized which is not adjustable. However, it has been found that a pump 3 which is adjustable similar to pump 5 works very well, the adjustment of pumps 3 and 5 bearing a relation to each other so that they can be simultaneously adjusted to change the speed of the engine. In a similar manner, if commencement and termination of injection are to be controlled by pump 3, then it would necessarily be pump 3 which would be adjustable, and a non-adjustable pump 5 could be employed.

As pump 5 need only supply fluid for opening the nozzle valve, its delivery need not be as large as the delivery of the conventional fuel pump. It is therefore possible to get more accurate adjustments and quicker responses in pump 5 in order to actuate the nozzle valve than is possible in a conventional fuel pump which operates to both inject fuel and actuate the nozzle valve. This is an added advantage of the present invention.

Pumps 3 and 5 may be operated from a common cam shaft (not shown) and in such case they would be on the same side of the internal combustion engine, indicated generally by the reference numeral 21 (Fig. 3). However, it has been found desirable to employ separate cam shafts for pumps 3 and 5. These cam shafts can be arranged end to end so that the arrangement of the pumps can be the same as when a single cam shaft is employed. The purpose of employing separate cam shafts is to provide for adjustment of one relative to the other in order that the relative action of the plungers of pumps 3 and 5 can be predetermined. Ordinarily the plunger 12 of pump 3 will start its stroke before the plunger 19 of pump 5 and the cam shafts will be so adjusted, the cam shaft for pumps 5 being adjustable and the cam shaft for pumps 3 being fixed.

Nozzle 2 is disposed over the center of the engine cylinder 22 into which it injects fuel, and is supported by the cylinder head in its vertical position shown in Fig. 1. Nozzle 2 includes a casing 23 which has a fuel receiving part or chamber 24 which is connected to pipe 4 by an inlet port 25 and which opens into the engine cylinder 22 by means of a passage or injection port 26 and jets 27. A valve seat 28 is formed around the chamber end of passage 26 and a nozzle valve 29, forming a part of a valve element 30, normally engages this seat, closing passage 26.

Casing 23 further has a valve-actuating fluid

chamber 31 which is connected to pipe 6 by an inlet port 32. A cylinder 33, of a smaller diameter than the chamber 31, opens at one end into chamber 31 and a piston 34 is disposed in the nozzle cylinder. Piston 34 is connected to nozzle valve 29 by a valve stem 35 which extends through chamber 31 and through a guide-forming passage 36 extending from chamber 31 to chamber 24. The valve stem 35 fits in close sliding engagement in the guide, preventing passage of fluid from one chamber to the other chamber. However, if the fluid pumped by pump 5 is fuel oil, then obviously intermingling of the contents of the chambers will be immaterial.

Casing 23 further has a chamber 37 in which is disposed an energized spring 38. In the drawing the casing is shown formed of two parts, namely a body 39 and a hollow cap 40, the cap providing chamber 37 and being secured to the body by threads 41. The spring presses at one end against the cap and at the other end against a seat 42 which is supported on a projection 43 formed integrally with the piston 34, the projection, piston, valve stem and nozzle valve all being integral parts of the valve element. Thus spring 38 holds the nozzle valve 29 against seat 28, normally closing passage 26, and returns nozzle valve 29 to this position after it has been raised by fluid from pump 5. A stop 44 is provided in the cap limiting the lifting of the valve element. While the pump 5 has been described as adapted to open the nozzle valve and the spring 38 to close it, it will be understood that this may be reversed, if desired, the pump 5 then being adapted to close the nozzle valve and the spring 38 to open it.

The particular construction of nozzle 2 shown and described is by way of illustration only, and various other suitable designs may be employed. All such various types of nozzles are contemplated as within the scope of the present invention.

Valve stem 35 is of a smaller diameter than piston 34, thereby providing a shoulder or piston head 45 against which the valve-actuating fluid operates.

As pump 5 operates to merely push the piston upward, the valve-actuating fluid may be a fluid which is trapped between the pump plunger 19 and the piston 34. However, as considerable heat is generated in the valve-actuating fluid, it is contemplated bleeding off a small amount of fluid through a bleeder port 46 formed in the chamber 31 for each operation of the plunger 19. This fluid is replaced by fluid entering cylinder 15 through pipe 17. The fluid which passes through port 46 is returned to the source of supply by pipe 47.

One of the ways of operating the fuel injection device of Fig. 1 is as follows: Fuel under pressure is pumped to chamber 24 by pump 3 and fluid under pressure is pumped to chamber 31 by pump 5. When the pressure in chamber 31 is sufficient to overcome the resistance of spring 38, the nozzle valve 29 is lifted off the seat 28, and, due to the operation of plunger 12, the fuel is injected into the engine cylinder. As the fuel will be at a high pressure in chamber 24 before nozzle valve 29 is lifted, injection will commence very quickly, insuring the injection of properly sprayed fuel and eliminating the dribbling in of poorly sprayed fuel, which dribbling often occurs when the nozzle valve is opened by the fuel under pressure. When plunger 19 has reached the end of the delivery portion of its

stroke the pressure in chamber 31 is dropped and spring 38 quickly returns piston 34 which effects rapid closing of nozzle valve 29. Fuel is being injected into the engine cylinder in properly sprayed condition up to the moment nozzle valve 29 closes, as plunger 12 is still on the delivery portion of its stroke. Thus dribbling is prevented at termination of injection. The harmful effects of dribbling are well known and no further comment is deemed necessary. Suffice it to say that if poorly sprayed fuel enters the cylinder, then poor combustion results.

Pump 3 is adapted to supply fuel properly to the engine at low speeds as well as at high speeds, for although at low speeds the pump plunger has a reduced velocity, this is compensated for by the fact that the pump can pump a large supply of fuel under pressure, no part of the plunger stroke being needed for other steps. Thus at reduced speeds, when the nozzle valve 29 is raised, the fuel in chamber 24 is under suitable pressure to properly spray it, and to inject it at the desired rate.

As the purpose of the pump 3 is to supply the fuel, the required pressure in pipe 4 may be produced thereby to give the desired fuel injection at the various speeds of the engine regardless of the various pressure waves that may be produced in pipe 4 as these have no effect upon the operation of the valve.

As the purpose of the pump 5 is to operate the valve, a required valve-operating pressure produced thereby in pipe 6 may be provided for, taking into account the relative size of piston 34 and strength of spring 38, such that there will be no pressure waves produced in pipe 6 of a magnitude sufficient to operate the valve.

There is an injection device 1 for each cylinder of the engine, as shown in Fig. 3. However, as pump 3 functions only to supply fuel under pressure to chamber 24, it is not necessary that there be a pump 3 for each cylinder. Thus, in Fig. 2 a modification is shown in which a single pump 3' provides fuel to a plurality of injector nozzles 2', all the pipes 4' branching from a single supply or pipe 48. The pump 3' is shown similar to pump 3. However, as it must pump more fuel than pump 3, it should be larger in order to maintain a pressure in pipe 48 suitable for injection, or if desired it can be given

more reciprocations per engine crankshaft revolution. That is to say, pipe 48 acts as a reservoir for fuel under pressure so that a supply is always available, check valve 13' preventing backward flow of fuel through pipe 48. Pump 3' may take care of several injector nozzles, depending upon its pumping capacity. Thus, for instance, in a six-cylinder engine, there might be three pumps 3' instead of six, as in the embodiment of Fig. 1.

While there have been hereinbefore described approved embodiments of this invention, it will be understood that many and various changes and modifications in form, arrangement of parts and details of construction may be made thereto without departing from the spirit of the invention, and that all such changes and modifications as fall within the scope of the appended claim are contemplated as a part of this invention.

The invention claimed and desired to be secured by Letters Patent is:

Fuel injection apparatus for supplying fuel to an internal combustion engine cylinder comprising a casing having a fuel injection port in one end thereof provided with a valve seat, a fuel chamber adjacent said seat, a piston cylinder, and a wall separating said chamber from said cylinder having an orifice extending therethrough; a unitary valve element including a control valve for said seat, a piston in said cylinder spaced from said wall providing a chamber for working fluid, and a stem extending through and closing said orifice and rigidly connecting said valve with said piston; a pumping device communicating with said fuel chamber for supply of fuel thereto; another pumping device communicating with said working fluid chamber for supplying working fluid thereto and for alternately producing fluid pressure and release of same therein whereby under said pressure said piston is moved in one direction to move said valve to port-open position; and a spring bearing on said piston for moving said piston in the opposite direction when said pressure is released for moving said valve to port-closed position, said spring being compressed by said piston during its first said movement.

WILLIAM M. NICHOLS.
